UNITED STATES PATENT OFFICE.

FRANK J. HOLMES, OF REVERE, MASSACHUSETTS.

METHOD OF SECURING ABSOLUTE REGISTRATION IN PRINTING FOR EMBOSSED, SCORING, AND DIE-CUTTING.

No. 888,886.

Specification of Letters Patent.

Patented May 23, 1908.

Application filed June 16, 1907. Serial No. 273,154.

To all whom it may concern:

Be it known that I, FRANK J. HOLMES, of Revere, in the county of Suffolk and State of Massachusetts, a citizen of the United States, have invented a new and useful Improved Method of Securing Absolute Registration in Printing for Embossing, Scoring, and Die-Cutting, of which the following is a specification.

My invention is applicable especially to lithography in cases where a design is repeated at one impression on different parts of a sheet which sheet is afterwards to be separated into a number of smaller sections 15 or sheets each containing one of said designs, which section is then to be embossed or to receive another impression. In such case the absolute registration of each section with the embossing die or another block from 20 which the final impression is to be taken is essential in order to secure perfect work.

Heretofore each sheet has been handled separately for the best results, being cut into sections by hand and trimmed along predetermined lines and then fed to the finishing press. This is a laborious and expensive process, taking considerable time when an edition runs up into the thousands as is usually the case, and requiring great care in order 25 so that the edges of the sheet may co-operate with the gages to center the work properly in the press which is to give the final impression.

My invention consists in making a number 30 of incisions along approximately the edges of each sheet upon two or more sides thereof, and also along approximately the line upon which the sheet is to be divided into sections, these incisions being made preferably in a press and simultaneously with one of the earlier impressions upon the sheet and being of peculiar shape having a portion or register adapted to be fed against the gage of the embossing press with its ends extending 35 therefrom towards the trimming or separating line and then cutting a number of these sheets simultaneously, for example, by the ordinary guillotine knife, along a line which intersects both ends of each incision.

It will be seen that not only will the sheet be separated or trimmed, but the portion of the sheet surrounded by what I have termed the incision and the cut made by the guillotine knife will be separated from the rest of the 50 sheet and will expose the register on the sec-

tion so that it will be available to engage with the gage in the subsequent embossing or printing press and so center the section for its subsequent impression. It will also be seen that as the cutters making the incision may be set in the printing frame with the block carrying the design, the incisions will always bear the same relation upon the sheet with the designs. Moreover, when the ends of the incisions extend a little distance—say 55 3/16 of an inch from the register portion thereof—the pile of blanks need not be placed under the guillotine knife with absolute accuracy so long as the cut crosses the ends of the incision, as such a cut in separating 60 the sheet into sections or trimming the sheet, necessarily exposes that portion of the edge which is to be placed against the gage to register therewith.

My invention will be understood by reference to the drawings where I have shown means by which my method is carried out and various steps thereof.

Figure 1 is a plan of a sheet after it has received one or more impressions, showing the 65 incisions referred to. Fig. 2 shows in addition the lines upon which the parts of the sheet are to be separated and the sheet trimmed. Fig. 3 shows a section of the sheet which has been separated and trimmed 70 and is ready for the final impression. Fig. 4 shows one of the knives with which the incisions referred to are made, and Fig. 5 shows a printing frame or chase in which the design blocks and knives have been set up. 75

In Figs. 1 and 2 the design is shown repeated upon two parts A, A¹ of the sheet, which parts are to be separated along the dotted line a. In Fig. 2, a¹, a² represent the lines along which the marginal strips are to 80 be cut off in trimming the sheet.

B, B¹ are incisions made by a knife such as is shown in Fig. 4, which knife is set up in the printing frame in the ordinary way of setting up type, etc., as will be seen from Fig. 5. 100 The printing frame or chase C, there shown, is of the ordinary rectangular character and contains blocks D upon which are the designs from which the impressions are to be taken.

E, E are the knives each of which is set into a frame and wedged into place by furniture and quoins in the ordinary way. The blades e, e project sufficiently beyond the face of the design block D to cut into the 110

sheet when the impression is made. The knife is shown in Fig. 4 comprising a blade approximately crescent shaped, the main portion e making the registering portion of the incision which is to engage the gage in the embossing press and having two horns e^2, e^2 extending therefrom at an obtuse angle as shown. I prefer to set these knives in the manner shown, namely, —in such a way that 10 two will be approximately upon the line of separation of the parts of the sheet and two parallel therewith upon the short side and two upon the longer margin of the sheet, but their arrangement will depend upon the location 15 of the gages upon the press upon which the final impression is to be given. The straight or register edges represented by the lines f, f (see Fig. 3), will engage the gages on the press and bearing always the same relation 20 to the design on every section, will cause that design to register accurately.

When a sheet has been taken from the press on which the incisions are made it may be laid upon a pile of like sheets and thereafter 25 the pile may be cut at one operation by a guillotine or steam cutter in the ordinary way of separating sheets, but as the line of separation cuts across the ends of the incisions made by the cutter it will be seen that 30 the waste g lying between the cut and each incision will fall out leaving the edge f exposed. It will also be seen that this cut need not be absolutely accurate owing to the 35 length of that part of the incision made by the horns e^2 of the knife which allow for a slight inaccuracy in the placing of the sheet with relation to the guillotine knife. This irregularity or variation may be as much as 40 $3/16$ of an inch, that is, as much as the distance of the straight edge of the knife blade is from the edge of the frame in which it is set. The knife blade may be of any convenient shape, so long as the incision which it makes will coöperate with the cut of the 45 guillotine. It is best made of a single blade set against a shank e^3 against which it is clamped by a clamp e^4 and screws e^5 . When the ends or horns e^2, e^2 are at an angle to each other they serve as guides to guide the registering portion of the incision towards its position 50 against the gage in the press.

In using the term "impression" in this specification and in the claims I mean to include either the act of making an impression in ink which in color work after the first impression requires accurate registration where a second color is to be added, or such impression as will result in embossing a figure upon a sheet, or scoring, or die cutting. In using 55 the term "edge" in reference to the register-

ing portion of the sheet I mean to include any portion of the edge of the sheet, however minute, which may be exposed in the manner described and may serve with a gage properly shaped to properly register the sheet. 65

What I claim as my invention is:—

1. The method above described of securing absolute registration of a sheet whereon a plurality of designs are printed which consists in making incisions in the sheet near the line 70 of separation of one design from another, each incision being shaped for the greater part of its length to engage a gage of predetermined shape, the ends of each incision projecting beyond the predetermined line of 75 separation between the said design and the one adjacent to it, and then separating the said design from the one next it by a cut extending across the ends of said incision whereby the material between said incision 80 and said cut will be removed and the edge of said incision will serve as a register to engage a gage as described.

2. The method above described of securing absolute registration of series of sheets which 85 consists in making incisions in each sheet at the time of impressing a design thereon, each incision having a registering edge and then trimming the sheet whereby the registering edges will be exposed. 90

3. The method above described of securing absolute registration of a series of sheets which consists in making incisions in each sheet at the time of impressing designs thereon, then separating each sheet into sections 95 by a cut crossing each incision at two points whereby the waste exposed by said cut will be separated therefrom exposing the register gage line.

4. The method above described of securing 100 absolute registration of a series of sheets which consists in making a series of crescent-like incisions therein simultaneously with the printing of designs thereon and then separating a plurality of such sheets superimposed 105 into sections by a cut crossing the horns of each incision as described.

5. The method above described of securing absolute registration of a series of sheets, which consists in making incisions in each 110 sheet at the time of impressing a design thereon, each incision being shaped to be crossed at two points by a cut and then trimming the sheet by a cut crossing such incisions at two points, as set forth.

FRANK J. HOLMES.
